UNITED STATES PATENT OFFICE.

PETER J. SMITH, OF IDAHO SPRINGS, COLORADO.

ORE-CAR.

SPECIFICATION forming part of Letters Patent No. 695,844, dated March 11, 1902.

Application filed March 25, 1901. Serial No. 52,841. (No model.)

To all whom it may concern:

Be it known that I, PETER J. SMITH, a citizen of the United States of America, residing at Idaho Springs, in the county of Clear Creek 5 and State of Colorado, have invented certain new and useful Improvements in Ore-Cars; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in ore-cars, my object being to make it practicable to have the load centrally located and bear equally on the two pairs of wheels of a dumping-car. As heretofore constructed the dumping extremity of these cars projects beyond the wheels farther than the rear extremity in order that the car may be ready to dump as soon as its rear extremity is released. This arrangement results in throwing the greater portion of the load on one pair of 25 wheels, which are thereby unequally worn. There is also a tendency on the part of the car to tip over bodily upon striking an obstacle on the track. Hence my object is to overcome these difficulties; and to this end the invention consists of a car whose body portion is manually movable endwise on the revolute platform of the truck, so that while normally the load is equally balanced on the truck the car-body may be shifted when the 30 car has reached the dumping point or station.

Having thus briefly outlined my improvement and stated the objects to be accomplished thereby, I will proceed to describe the same in detail, reference being made to the accompanying drawings, in which is illustrated an embodiment thereof.

In the drawings, Figure 1 is a side elevation of my improved car shown in its normal position—that is to say, balanced on the platform or truck. Fig. 2 is a similar view showing the car in the dumping position. Fig. 3 is a section taken on the line $\alpha\alpha$, Fig. 4. Fig. 4 is a section taken on the line AA , Fig. 1. Fig. 5 is a section taken on the line yy ,

Fig. 4. Fig. 6 is a section taken on the line zz , Fig. 5.

The same reference characters indicate the same parts in all the views.

Let the numeral 5 designate the car-body, and 6 the platform, revolutely mounted on the truck 7. The car-body is connected with the platform 6 by means of a shaft 8, journaled in bearings 9, fast on the platform. This shaft is also journaled in the forward extremities of track-rails 10. The upper portion of each of these rails is T-shaped in cross-section and engages a groove of counterpart shape formed in a bar 12, fast on the bottom of the car, whereby the car-body is slideable endwise on the platform and at the same time mounted 65 to turn on the shaft 8 as an axis to assume the dumping position. It will be observed that when the car-body dumps (see Fig. 2) the track-rails 10 tip therewith by virtue of the connection between the T-shaped rails 70 and the bars 12.

Fast on the shaft 8, outside of each rail 10, is a gear or pinion 13, which engages a cogged rack 14, fast on the bottom of the car-body outside of the bar 12. The shaft 8 protrudes 75 beyond the body of the car on one side, and to this protruding extremity is made fast a toothed wheel 15. A hand-lever 16 is pivoted on the shaft adjacent the toothed wheel. On this lever is pivotally mounted a dog 17, one 80 extremity of which is connected with a spring-actuated rod 18, connected with a handpiece 19, pivoted on the body of the lever, the arrangement being such that the dog 17 is normally held disengaged from the toothed 85 wheel. When the handpiece 19 is grasped by the hand of the user, the dog will be thrown into engagement with the wheel, whereby the shaft may be turned in either direction, as desired.

The body of the car is connected at the rear with the truck-platform by means of a depending hinged plate or latch 20, arranged to engage a projection 21. This latch 20 is connected, by means of a link 22, with a lever 23, fulcrumed on the rear extremity of the car-body, as shown at 24. The latch may be disengaged from the platform by means of this

lever. This construction also prevents the car from sliding forward accidentally on the track-rails, as otherwise might be the case on inclines.

5. The hinged door 5^a of the car-body is normally locked by a dog 25, pivoted on a T-shaped block 26, slideable in a counterpart way 27, formed on the bottom of the car. One arm of the dog 25 is connected, by means 10 of a rod 28, with the shaft 8, which is journaled in the rear extremity of the rod, as shown at 28^a. When the car-body is in its normal position, as shown in Figs. 1, 3, and 5, the dog 25 is held in a position to lock the 15 door 5^a closed. When, however, the car-body is moved to the dumping position, (see Fig. 2,) the dog is made through the instrumentality of the rod to assume the position shown in Fig. 2, allowing the car-door to 20 swing outwardly.

From the foregoing description the use of my improved ore-car will be readily understood. When it is desired to dump the car, the lever 16 is actuated to turn the shaft, 25 whereby the pinions 13, through the instrumentality of the racks 14, cause the car-body to move forward to the dumping position. Before moving the car-body to this position the latch 20 is disengaged from the projection 30 21. After the car-body has dumped its load and is tipped to the horizontal position it may be returned to its normal or balanced position by turning the shaft 8 in the reverse direction from its movement when moving the 35 car-body forward.

Having thus described my invention, what I claim is—

1. In a car the combination with a truck, of a track pivotally mounted thereon, and a 40 car-body slideable on the track.
2. In a car the combination with a truck, of a track hinged or pivoted thereon and a car-body slideable on the track and operatively connected therewith.
- 45 3. The combination with the car-truck and platform, of a track pivoted on the platform, and a car-body slideable on the track and mounted to move back and forth thereon for the purpose described.
- 50 4. The combination with a car-truck, of a track hinged or pivoted thereon and a car-body connected with the track and arranged to move back and forth in a direction at right angles to the axis of its pivot.
- 55 5. The combination with a car-truck of a shaft journaled in suitable bearings on the truck, track-rails pivoted on the shaft, and a car-body movable on the rails.
- 60 6. In a car the combination with a truck, of track-rails pivoted on the truck, the car-body movable on the rails in a direction at right angles to the pivot, and suitable means for shifting the car-body on the pivoted track-rails.
- 65 7. In a car, the combination with a truck,

platform and car-body, of rails pivoted on the platform and having T-shaped upper parts, bars fast on the car-body and having counterpart grooves with which the track-rails engage, and suitable means for shifting 70 the car-body on its track.

8. In a car the combination with the truck, platform and car-body, of a shaft journaled on the platform, a track pivoted on the shaft, the car-body being slideable on the track, a 75 gear mounted on the shaft, and a rack mounted on the car-body and engaged by the gear.

9. In a car the combination with a truck, platform and car-body, of a shaft journaled on the platform, a track mounted on the 80 shaft, the car-body being connected to slide on the track and turned therewith, a gear mounted on the shaft, a rack mounted on the car-body and engaging the gear, a toothed wheel fast on the shaft, and a lever for actuating said wheel.

10. The combination with a track, platform and car-body, of a shaft journaled on the platform, rails pivoted on the shaft, and having T-shaped upper parts, bars fast on the 90 car-body and having counterpart grooves engaging the T-shaped parts of the rails, racks fast on the car-body and engaged by the pinions, and suitable means for actuating the shaft to shift the car-body. 95

11. The combination with a truck, and a car-body, of a track hinged or pivoted on the truck, the car-body being slideable on the track and provided with a hinged door, means for locking said door in a closed position, 100 and a connection between the car-truck and said locking means whereby the latter is controlled as the car-body is shifted.

12. The combination with the car-truck, platform and car-body, the car-body being 105 slideable on the platform and having a hinged door, of a shaft journaled on the platform, and on which the car-body is pivoted, a connection between the shaft and car-body whereby the latter is shifted by turning the 110 shaft, a block slideable on the bottom of the car-body, a dog pivoted on the block and arranged to lock the car-body in the closed position, and a rod connecting the said dog with the shaft whereby the dog is automatically actuated as the car-body is shifted. 115

13. In a car the combination with a truck and a car-body, of a track hinged or pivoted on the truck, the car-body being slideable on the track, and means for locking the car-body against accidental forward movement. 120

14. In a car the combination with a truck and a car-body, of a track pivotally mounted on the truck, the car-body being slideable on the track, and suitable means for locking the 125 car-body against accidental forward movement, comprising a depending apertured plate hinged to the bottom of the car-body, and a projection on the truck adapted to enter the opening of the plate. 130

15. In a car the combination with a truck and a car-body, of a track hinged or pivoted on the truck, the car-body being slideable on the track, of a depending apertured plate hinged to the bottom of the car, a projection on the truck adapted to enter the opening in the plate, and means for disengaging the plate from the truck, comprising a lever ful-

crumed on the rear part of the car, and a link connecting the plate with the lever. 10

In testimony whereof I affix my signature in presence of two witnesses.
